ATTORNEY

UNITED STATES PATENT OFFICE.

SAMUEL K. HAWKINS, OF ELMIRA, NEW YORK, ASSIGNOR TO CLAY C. CORNER, OF COLUMBUS, OHIO.

TIE-PLATE FOR BRUSH-FILLINGS.

SPECIFICATION forming part of Letters Patent No. 431,770, dated July 8, 1890.

Application filed May 7, 1889. Renewed June 12, 1890. Serial No. 355,149. (No specimens.)

To all whom it may concern:

Be it known that I, SAMUEL K. HAWKINS, of Elmira, in the county of Chemung and State of New York, have invented a new and useful Improvement in Tie-Plates for Brush-Fillings, of which the following is a full, clear, and exact description.

My invention relates to an improvement in end tie-plates for brush-fillings, and has for its object to provide a plate which will effectually tie the ends of the brush-filling in position and permit the lower extremity of the filling to project outward beyond the perpendicular plane of the end of the brush.

The invention consists in the novel construction of the plate and in the combination of said plate with the brush block and filling, as will be hereinafter more fully set forth, and pointed out in the claims.

Reference is to be had to the accompanying drawings, forming a part of this specification, in which similar figures of reference indicate corresponding parts in all the views.

Figure 1 is an end view of a brush having my improved plate applied thereto. Fig. 2 is a side elevation of the same. Fig. 3 is a transverse section through the plate and a partial longitudinal section through the brush head and filling. Fig. 4 is a perspective view of a detached plate, and Fig. 5 is a transverse section of the brush.

The brush 10, to which the plate is especially applicable, consists of a block 11, provided with a series of longitudinal grooves 12 in the under face, in which grooves filling 13, of any desired character, is inserted to serve in the capacity of bristles, which filling is ordinarily held within the grooves by a wire rod 14, over which the filling is bent, which rod is secured in any approved manner at or near the ends of the block.

In securing the filling into the brush-block it is especially desirable that the said filling at the end of each row shall project beyond the end of the brush-block, as best shown at 15 in Figs. 2 and 3, in order that the brush may be used effectively to clean any surface—in the corners, for instance—without the end of the brush being brought in unpleasant contact with the walls. In order to permit of this construction and protect the upper ex-

posed ends of the filling, I provide a plate 16, illustrated in detail in Fig. 4, the general contour of which plate 16 is made to correspond, preferably, with the end contour of the brush-block 11, at which point the plate is adapted to be secured by nails, screws, staples, or equivalent fastening devices. 55

The inner face of the plate is indented or otherwise manipulated to form recesses 17, by means of which operation, if the plate is thin, the corresponding offsets will be produced upon the upper face of the plate, as illustrated in Figs. 1 and 2. The recesses 17 are so located in the plate that when the plates are secured to the ends of the brush-block 11 one recess will be immediately opposite the end of each row of filling, as shown in Fig. 3, the projection of the filling beyond the end of the brush-block being regulated 70 by the depth of the recesses.

Having thus described my invention, I claim as new and desire to secure by Letters Patent—

1. As a new article of manufacture, an end tie-plate for brush-fillings having a recessed inner face, substantially as shown and described. 75

2. As a new article of manufacture, an end tie-plate for brush - fillings provided with a series of indentures or recesses in the inner face, as and for the purpose specified. 80

3. As an improved article of manufacture, an end tie-plate for brush-fillings provided with recesses in the inner face, whereby corresponding offsets are produced upon the outer face, substantially as and for the purpose specified. 85

4. The combination, with a brush-block, and filling secured in the said brush - block in rows, the ends of which rows project beyond the end surface of the block, of a tie-plate secured to the ends of the said block and provided with recesses in the inner face corresponding in number with the rows of filling and registering with the ends of the rows of the said filling, substantially as shown and described. 95

SAMUEL K. HAWKINS.
